UNITED STATES PATENT OFFICE.

MARC SECKINGER, OF MONTBÉLIARD, FRANCE.

SAFETY-LOCK.

1,261,060.

Specification of Letters Patent. Patented Apr. 2, 1918.

Application filed August 11, 1913. Serial No. 784,255.

To all whom it may concern:

Be it known that I, MARC SECKINGER, a citizen of the Republic of France, residing at Montbéliard, Doubs, in the Republic of France, have invented certain new and useful Improvements in Safety-Locks; and do hereby declare the following to be a full, clear, and exact description of the invention, such as will enable others skilled in the art to which it appertains to make and use the same.

The present invention relates to a combination lock capable of being readily applied to a piece of furniture, a cupboard or other suitable locality. The invention is shown in a preferred form in the accompanying drawing wherein Figure 1 is a vertical section of the lock in locked position, Fig. 2 is a section on A—B in Fig. 1, Fig. 3 is a sectional view similar to Fig. 1, but showing the device in unlocked position, Fig. 4 is a rear elevation in unlocked position with the socket-carrying disk removed, Fig. 5 is a front elevation, Fig. 6 is a view similar to Fig. 4 but showing a locked position, and Fig. 7 is a view similar to Fig. 4, showing the method of changing the combination.

The front disk *n* which is suitably numbered for indication of combinations, as shown in Fig. 5, has a central circular rear hub *m*. A revoluble pin *q* is centrally placed in this hub and has a recess *r*. This pin may be turned in its socket at will by inserting a screw driver in the slot shown at the left in Fig. 3.

Around the hub *m* are fitted flat annular disks or tumblers, *l'*, *l''*, *l'''* lying one on the other. These disks are provided respectively with sliding pins or dogs *k'*, *k''*, *k'''*, whose outer extremities enter one or the other of a series of notches *p* in the outer annular disks or rings *i'*, *i''* and *i'''*. These latter rings are laid flatly on each other and are fitted revolvably around the inner disks *l'*, *l''*, and *l'''* respectively. The inner ends of the dogs *k'*, *k''* and *k'''* are adapted to enter the cavity *r* of the central pin *q* when turned in a given position (shown in Fig. 7).

The disks above described are confined in place by a rear plate or cover to which the hollow socket *a* is shown attached, which socket contains the actual bolt by which the locking effect is produced, and it is intended to be located in a suitable cavity in the article to be locked, in a well known manner.

Within the socket *a* is fitted the tilting bolt *b* pivoted upon a carrier *c* adapted to slide within the socket *a*, and provided with a threaded stem or rod *d*. An operating disk *e*, with a milled edge, has a hub entering the socket *a*, and is centrally threaded to receive the stem *d*. When the disk *e* is turned one way or the other it acts through the stem *d* and carrier *c* to place the bolt *b* either in the locked position (Fig. 1) or the unlocked position (Fig. 3).

Each of the disks *l'*, *l''*, and *l'''* is provided with a hole of proper size and so placed that the three holes can be brought into registry with each other directly behind the stem *d* to permit said stem to be thrust into said holes for unlocking, as shown in Fig. 3.

Each disk *l'*, *l''* and *l'''* is provided with a notch *o* placed so that all three notches may be made to register over the outer edge of a plug *g* of wedge shape, riding in a groove *h* having an inclined bottom and formed in the periphery of the hub *m*.

The registering of the notches *o* occurs when the holes for receiving the stem *d* are in the position shown in Fig. 3.

When the device is in locked position (Fig. 1) and the notches *o* are out of alignment, the plug *g* is forced back into a recess in the milled disk *e*, thus locking said disk and preventing operation of the main lock, both by preventing action of the wheel *e* directly and by preventing movement of the stem *d* by reason of the holes intended to receive it being out of registry.

When the disks *l'*, *l''*, and *l'''* are turned, however, into the position shown in Fig. 3, the notches *o* are in alignment, and, owing to the chamfered or pyramidal shape of the point of the plug *g*, the recess in the disk *e* acts when the disk is turned, to force back the plug up the inclined bottom *h*, so that its upper edge enters the aligned notches *o*. This is shown in Fig. 3.

The requisite movements of the annular disks, for bringing them into unlocked position are accomplished by the projections 1, 2 and 3, respectively, on the peripheries of the outer rings *i'*, *i''* and *i'''*, and by transmission of this movement from each ring to the disk within it by the respective dogs *k'*, *k''* and *k'''*. The numerals around the front plate shown in Fig. 5, guide this action.

When the device is locked and the stem *d* has been thrust fully forward and out

100

110

of engagement with the disks, these latter are turned in such a direction as to drive the inclined sides of the notches *a* against the edge of the plug *g*, thus forcing said plug back into the disk *e* as shown in Fig. 1.

To change the combination, the central pin *q* is turned to permit movement of the dogs *k'*, *k²* and *k³* inward, thus permitting the outer rings to be brought into new positions, after which the dogs are again pushed outward into engagement with new notches in the outer rings.

Obviously more than three sets of disks and rings might be used and various changes might be made in this device without departing from the scope of my invention, as I do not limit myself to the details herein shown and described.

What I claim is—

- 20 1. In a combination lock, a bolt, an actuating device adapted to move said bolt for locking and unlocking, a revoluble locking disk adapted to oppose direct resistance to the unlocking movement of said bolt and means for locking said actuating device controllable by movement of said revoluble locking disk, substantially as described.
- 25 2. In a combination lock, a bolt, a revoluble disk adapted to actuate the same for locking and unlocking, revoluble tumbler disks, and a movable plug adapted to lock said actuating disk, said plug being controlled by the positions of said tumbler disks, substantially as described.
- 30 3. In a combination lock, a bolt, a revoluble disk adapted to actuate the same for locking and unlocking, a central hub having a recess in its periphery which recess has an inclined bottom, a plug slideable in said recess and adapted to engage said disk, and tumbler disks revolubly mounted upon said hub and having notches capable of being placed in alinement over said recess in the hub, substantially as described.
- 35 4. In a lock, a hollow socket, a carrier slidably mounted therein, and having a threaded stem, a locking disk in front of said carrier and stem, a tilting bolt pivoted to said carrier, and an actuating disk threaded upon said stem, between said locking disk and said tilting bolt and having a portion of its periphery extending outward for purposes of manipulation, substantially as described.
- 40 5. In a lock, a hollow socket, a carrier slidably mounted therein and having a threaded stem, a tilting bolt pivoted to said carrier, an actuating disk pivoted upon said

stem, and means for locking said disk in a predetermined position, substantially as described.

6. In a lock, a hollow socket, a carrier slidably mounted therein and having a threaded stem, a tilting bolt pivoted to said carrier, an actuating disk pivoted upon said stem, tumblers behind said stem suitably pierced to receive the stem when properly adjusted and locking means for said disk controlled by said tumblers, substantially as described.

7. In a combination lock, a central hub, an annular disk revolubly mounted thereon, an outer ring mounted to revolve around said disk, and having a series of internal notches, a dog slidably mounted in said disk and adapted to engage any one of said notches, and means in said hub adapted to control the movement of said dog, substantially as described.

8. In a combination lock, a central hub, an annular disk revolubly mounted thereon, an outer ring mounted to revolve around said disk and having a series of internal notches, a dog slidably mounted in said disk and adapted to engage any one of said notches, and a revoluble pin in said hub having a recess adapted to receive one end of said dog, substantially as described.

9. In a combination lock, a central hub provided with a disk bearing a series of conventional signs such as numerals, a plurality of disks revolubly mounted on said hub, a slidably mounted dog on each disk, a ring revolubly mounted around each revoluble disk and adapted to be engaged by said dogs respectively, and an indicating projection on each of said rings, substantially as described.

10. In a combination lock, a socket having a side opening, a carrier adapted to slide therein, a tiltable bolt pivotally secured to said carrier and adapted to be pushed out through said side opening when said carrier is pushed inward, said bolt having a plane portion adapted to engage with the end of said carrier when in locked position, actuating means for the carrier and for locking said actuating means when said bolt is pushed outward, substantially as described.

In testimony whereof, I have affixed my signature, in presence of two witnesses.

MARC SECKINGER.
